2,085,473

FLEXIBLE IMPERVIOUS AND WEATHER-
PROOF MATERIAL

William Wallace Rowe, Cincinnati, Ohio, assignor
to The Paper Service Company, Leckland, Ohio,
a corporation of Ohio

Application January 30, 1931, Serial No. 512,311

16 Claims. (Cl. 154—50)

The primary object of my invention is the provision of a novel flexible impervious and waterproof material having a wide usefulness as hereinafter pointed out. Another object is the provision of a composite material of creped paper and woven fabric or the like, in which the fabric or reinforcing structure is completely encased in a protective structure, and completely coated with a protective substance. Still another object 5 of my invention is the production of a structure of this type having special characteristics as will hereinafter be more fully described.

The more specific objects of my invention will be apparent from the ensuing description, and 15 reference is now made to the drawing forming a part hereof.

In the drawing:

Figure 1 illustrates semidiagrammatically an apparatus suitable for the formation of my product in its preferred form, together with the product as so formed.

Figures 2, 3, and 4 show in section several forms of my product.

While the structure of the product is itself novel with me, I also claim novelty in the product having the specific and preferred qualities imparted by the method of formation which I shall describe as a specific embodiment of my process invention.

In my Reissue Patent No. 17,633 I have set forth and claimed a method of creping paper by means of a thermo-plastic adhesive substance such as asphalt or other bitumen, and the joining thereof to a backing material. By this method 25 I have made composite fabrics consisting of a layer of creped paper joined to a layer of burlap, and such fabrics have found a wide usefulness in a number of arts. An important use is in the manufacture of bags employed for the shipment 30 of fertilizer and the like, in which the burlap, lying outside the paper lining furnishes the requisite additional strength, while the paper lining makes the bag relatively impervious.

The particular creping process referred to results in the production of a crepe of fine and velvety character, in which a great amount of stretch 45 may be incorporated when desired, and which is characterized by a commercial absence of skips. In all of these particulars it is superior to a 50 water-creped sheet, and the particular characteristics of the crepe are produced by a positive binding action of the thermo-plastic adhesive between the paper web and the creping cylinder. It will be obvious that this process delivers a 55 creped sheet which is coated, and in which the

coating is substantially continuous within and without the crinkles. This also is advantageous in making for a completely coated sheet in which all of the stretch is retained, because the paper is creped conjointly with the thermo-plastic binder. Where paper previously creped is to be coated with bitumen, in order to attain anything like a complete coating, a considerable portion of the stretch has ordinarily had to be removed from the paper; and furthermore water-creped sheets are characterized by a relatively coarser crepe, skips, i. e. uncreped portions, and in general a smaller degree of stretch in proportion to the thickness of the creped web. When following out the process of my reissue patent hereinabove referred to, or modifications thereof, it is possible to use the thermo-plastic adhesive employed in the creping operation to join the burlap or other backing material to the sheet; and this is further advantageous in that it makes for economy in 10 manufacture, and enables me to control the amount of adhesive used.

In order that a bag or other article to be made therefrom shall be satisfactorily impervious and moisture-resistant, it is the practice to use a 15 thermo-plastic waterproof adhesive such as asphalt. This has to be relatively carefully controlled as to amount so that it will not penetrate unduly to the far side of the burlap and produce 20 stickiness under ordinary conditions, yet it must be sufficient in amount to provide a proper adhesion and waterproofing. Thus in some instances, particularly where bags of the character hereinabove described have been stacked one upon another so as to be subjected to considerable pressure, and particularly in summer weather or 25 warm climates, or when filled with hot material, the bitumen has shown a tendency to penetrate through the burlap and to stick adjacent bags together or render the bags somewhat difficult 30 to handle. The burlap cannot become truly saturated, and under conditions of dampness and the like, the burlap may deteriorate and rot. This is not ordinarily of primary importance in bags, but it has prevented the use of the composite material aforementioned in other arts such as require 35 a higher degree of weatherproofness and the like, for example, tarpaulins for the temporary coverage of cement work or for other construction uses. For such uses, the fabric described would be much improved even for the manufacture of bags if the amount of adhesive substance could be relatively increased, but for 40 the reasons given this has not been found possible.

My invention contemplates the provision of a 45

composite fabric comprising two layers of paper, at least in part, with the backing or reinforcing material inter-leaved between them, and a specific embodiment comprises a layer of burlap adhesively secured between layers of creped paper. Such a product may be formed by taking two layers of previously creped paper and cementing a layer of burlap or the like therebetween; but I prefer to form it, as will now be clear, from layers of paper creped by means of a thermoplastic adhesive substance as hereinabove described, the thermo-plastic substance employed in the creping being used in part at least as the adhesive cementing the paper to the burlap. Other materials of fibrous character, whether woven, spun, or not, may be substituted for the burlap, but for many uses, burlap will be found preferable and inexpensive. It will be understood that for some uses the coating of paper upon one or both sides of the composite material need not be coextensive with the backing material.

In a composite sheet such as my invention contemplates, the double facing of paper further locks the fibers and prevents their sliding and bunching at the seams, when the material is sewn. A sewn seam in a bag made of burlap alone is subject to enlargement at the needle holes under stress, because the coarse strands of the burlap can slip and be gathered together leaving a considerable opening behind them. This is less likely to occur when the burlap is faced with paper, as in the single lined product hereinabove referred to. But in the double lined product of my invention, any slippage of the strands is found to be effectually prevented. In some instances, particularly where expense prohibits it, it is not necessary to cover both surfaces of the burlap completely with the paper lining. So far as the sewn seam itself is concerned, the same result may be obtained by lapping the paper about the edge of the burlap, or by running a separate strip of paper in the seam positions upon the opposite side of the product. The selvage of the burlap or other reinforcing material may be caused to fall either at the side or bottom seams if desired.

Again, a double paper-faced material is easier to sew because in the single lined material the presser foot and feed dogs of the sewing machine tend to pick up asphalt through the burlap. My new product is exceptionally neat in appearance, extremely tough and resistant to puncture, and easier on the hands of workmen. In some instances old burlap may be used in making it, because printing and the like on the burlap is obscured; and where strength is a factor, I have found that I can use lighter burlap in my product with attendant economy without sacrificing strength.

In the single lined product heretofore made, as has been noted, the asphalt is frequently caused to penetrate through the mesh of the burlap either by heat alone or by pressure or a combination of the two. Whenever the asphalt penetrates the surface of the backing material, the fabric is rendered unsightly, bags made of it are apt to stick together and any printing upon the surface thereof is obscured. The material of my invention is completely effective in keeping the asphalt or other combining adhesive from coming through under pressure because of the relatively non-porous nature of the paper surface as compared with the burlap or other backing surface. Under conditions of heat, however, as when hot material is loaded into the bags, there may be a tendency for a bituminous adhesive to

stain through the paper unless precautionary steps are taken. Thus, while the bitumen will not come through the paper surface in any such quantity as would cause sticking, there may be sufficient saturation of the outer paper layer to cause a darkening of the surface thereof in spots. It is within the scope of my invention to treat the outer paper layer to render it more impervious where the product is intended for use under extreme conditions.

I have found it possible to coat the surface of the paper next to the bitumen or other staining adhesive, or to saturate the layer of paper with such materials as glue, dextrine, starch or the like, in water solution. This is usually done, and the paper dried, prior to the adhesive joining of the paper and the backing material, and it may be done prior to the creping of the paper. I may also employ such materials as rubber latex; and I have found all of these substances effective in preventing the asphalt layer from staining through. When using latex, care must be taken to avoid having too thick a layer of latex upon the surface of the paper next to the bitumen, since this may reduce the adhesion between the paper and the bitumen. Impervious paper such as parchment, or papers which have been made with an incorporated sizing substance, may be used without departing from the spirit of my invention, and also adhesive substances which do not have a staining effect upon penetration may be used instead of bitumen, in forming my composite product. Rubber latex, if applied to the paper prior to creping, has the advantage that the impervious character of the sheet is less liable to be broken in the creping operation, than when some other sizing substances are used. Where pre-creped papers are being coated with asphalt and applied to burlap without disturbing the creping to any great extent, it is possible to use a wide variety of sizing substances with entire satisfaction. Where it is not objectionable to have the inside of the bag or other structure, stained black by asphalt penetration, the outside layer alone may, of course, be treated.

I have illustrated in Figure 1 semi-diagrammatically a mechanism suitable for the production of my preferred fabric. I have shown a creping cylinder 1 adapted to be carefully controlled as to temperature, to the surface of which I apply a coating of thermo-plastic substance by means of the coating rollers 2, the outermost of which turns in a pan 3 of the thermo-plastic substance. A web of paper 4, is led to the creping cylinder and is held thereto by the thermo-plastic adhesive substance which will preferably be tempered by the temperature controlling effect of the creping cylinder. The paper may be forced into contact with the creping cylinder by means of a pressure or back-up roll 5, and it is removed from the cylinder by a creping doctor or knife 6. As removed, it is in creped form with a coating of the thermo-plastic adhesive upon its underside. Before this coating has lost its tackiness, I conduct to the coated side of the web 4, a layer of burlap or other backing material indicated at 7 and press it into contact with the adhesive by means of rolls 8.

I also prefer to provide a second creping machine of similar construction, having a creping roll 1a, coating rolls 2a, a pan 3a, a back-up roll 5a, and a doctor or knife 6a, as will now be readily understood. A second web of paper 4a is creped in this second mechanism, and is conducted to the burlap coated, creped sheet 4 and 75

pressed thereagainst by means of rollers 8a, the coated side of the creped web 4a lying next the burlap. The burlap is fed preferably from a roll 8, and the paper webs 4 and 4a respectively, from 5 rolls 10 and 10a.

This procedure results in the production of a composite material comprising a reinforcing or body substance 7 and layers of creped paper 4 and 4a cemented thereto on either side. Where the 10 body substance is thin enough, and burlap is such a substance, the combined coats of adhesive upon the creped paper webs will preferably penetrate the body substance and seal the strands thereof, surrounding them more or less completely. In 15 this way the burlap, where burlap is used, may be made water-resistant, and resistant to rotting or disintegration. Where desired, the body substance may first be saturated or treated with a 20 bituminous substance or preservative, or a protective substance of any character desired before it is run between the paper webs. It will be obvious that various modifications may be made in my procedure without departing from the spirit of my invention.

25 In Figure 2, I have shown in section my composite fabric in which the burlap or other reinforcement 1 is interleaved between layers of creped paper 4 and 4a. In Figure 3, by lapping the edges of the paper layer 4b over the edges of the burlap, as at 11, I have produced a product which is double faced in part. Such a product is 30 particularly adaptable to the manufacture of bags, where the blank may be so cut that the double faced portion forms the seams. In Figure 35 4, the lower paper web has been lapped over the edges of the burlap and over or beneath an upper paper web. This forms an exceptionally strong product having at least two of its edges closed with paper. The advantage of this product for use as 40 a weatherproof covering will be apparent.

As a composite fabric, my material is relatively unlimited as to the amount of adhesive or saturant which may be employed in the body substance, and the disadvantages hereinabove noted 45 of the composite materials heretofore used are not apparent in the material of my invention. My material is, of course, doubly impervious, and in practice where I have used asphalt as a creping and adhesive substance, I have found that no 50 amount of pressure to be encountered under the condition heretofore mentioned will be sufficient to drive the adhesive substance through the paper so as to cause sticking. My material is commercially waterproof, and may be used as tarpaulins 55 and the like. In the manufacture of bags it has the advantages which will be obvious from the foregoing description, and an additional advantage in that the amount of binder or adhesive substance employed serves in great measure to seal 60 the needle holes of a sewn bag so as to prevent the sifting of its contents. The creped paper may be coated or colored on the side away from the burlap as desired, or may readily be printed, or otherwise decorated. This is an additional 65 advantage in bags, inasmuch as printing upon burlap is not particularly satisfactory. I may also use my product for wall covering or other decorative uses. By my process, as many alternate 70 layers of creped paper and backing or body substance may be joined together as desired. I am not limited to asphalt as a thermo-plastic adhesive substance, but I may use any of the various tars, pitches, waxes, gums, bitumens, resins and the like. I am not limited to the use of burlap as a 75 body or reinforcing substance, since I may em-

ploy other materials, either woven or felted, or not, as desired, although for the uses herein particularly mentioned, I prefer either a woven textile fabric, or a material comprising strands, cords or filaments in a structure penetrable by the combining adhesive. These strands or filaments, where they have no preformed interrelationship, may be laid upon the surface of the paper layers in any way desired, and covered by the other, or run in between the paper surfaces with or without rearrangement. Where I employ strands of a material liable to loss of strength through atmospheric or moisture conditions, such as paper strips, strands or twisted paper cords, an advantage of my invention is that these strands may be surrounded and sealed by the adhesive and the adjacent paper layers against the said conditions.

Having thus described my invention, what I claim as new and desire to secure by Letters Patent is:

1. A composite material comprising a body substance cemented by means of a thermo-plastic adhesive between layers of creped paper, one of said layers being impervious to said adhesive.

2. A composite material comprising a body substance cemented by means of a bituminous adhesive between layers of creped paper, one of said layers being treated with a sizing substance whereby it is impervious to bitumen.

3. A composite material comprising a body substance cemented by means of a bituminous adhesive between layers of creped paper, one at least of said layers being treated with rubber latex.

4. A composite material comprising at least one layer of cloth and a layer of creped paper cemented thereto by means of a staining adhesive and at least one continuous layer of stain preventing coating associated with said paper.

5. In a composite fabric, a layer of cloth and at least one layer of creped paper in cementitious union therewith, a layer of staining adhesive located between said cloth and said paper and a continuous layer of stain preventing material also lying between said cloth and said paper.

6. In a composite material, a layer of backing substance and a layer of crepe paper in adhesive union therewith, a layer of staining adhesive located between said paper and said backing material and a continuous layer of stain preventing substance located between said paper and said adhesive layer.

7. In combination, a layer of cloth and a layer of paper cemented together with a bituminous adhesive and a continuous layer of stain preventing coating associated with said paper layer.

8. In combination, a layer of cloth and a layer of paper in adhesive union, a bituminous adhesive layer located between said cloth and said paper, a continuous layer of stain preventing coating associated with said paper layer and a decorative material located with respect to said paper layer so as to be protected by said stain preventing layer.

9. In combination, a layer of cloth and a layer of creped paper in adhesive union, a layer of bitumen serving as the adhesive and located therebetween, and a continuous layer of stain preventing coating associated with said paper layer whereby decorative material may be imposed upon the paper side of said composite fabric without danger of said bituminous coating or the constituents thereof staining said decorative material.

10. In a composite material, a layer of backing substance and a layer of creped paper in adhesive union therewith, a layer of staining adhesive located between said paper and said backing substance, and a continuous layer of stain preventing coating associated with said paper.

11. In combination in the order named, a layer of paper treated so as to be non-susceptible to staining, a layer of staining adhesive and a layer 10 of cloth, all in adhesive union.

12. A composite material comprising a layer of cloth and a layer of creped paper cemented thereto by means of a staining adhesive and at least one continuous layer of barrier material 15 impervious to said adhesive associated with said paper.

13. In combination a body substance and a layer of paper in adhesive union, a bituminous adhesive layer located between said body substance and said paper, a continuous layer of stain preventing coating associated with said paper layer, and a decorative material located with respect to said paper layer so as to be protected by 20 said stain preventing layer.

25. 14. In combination a body substance and a

layer of creped paper in adhesive union, a layer of bitumen serving as the adhesive and located therebetween, and a continuous layer of stain preventing coating associated with said paper layer whereby decorative material may be imposed upon the paper side of said composite fabric without danger of said bituminous coating or the constituents thereof staining said decorative material.

15. In a composite material, a layer of backing substance and a layer of creped paper in adhesive union therewith, a layer of staining adhesive located between said paper and said backing substance, and a continuous layer of barrier material 15 impervious to said adhesive associated with said paper.

16. In a composite material, a layer of backing substance and a layer of creped paper in adhesive union therewith, a layer of staining adhesive located between said paper and said backing substance, and a continuous layer of barrier material 20 impervious to said adhesive associated with said paper, said composite material having a decorative coating.

WILLIAM WALLACE ROWE. 25
